DESIGN FOR A HAT

Edward C. Sloan, Geneva, Ill., assignor to Jesse
B. Hawley, Geneva, Ill.

Application October 4, 1935, Serial No. 58,836

Term of patent 7 years

To all whom it may concern:

Be it known that I, Edward C. Sloan, a citizen of the United States and residing at Geneva, county of Kane, and State of Illinois, have invented a new, original, and ornamental Design for a Hat, of which the following is a specification, reference being had to the accompanying drawing forming a part hereof.

Fig. 1 is a top plan view of a hat embodying my new design;

Fig. 2 is a view in side elevation of the same; and,

Fig. 3 is a fragmentary sectional view taken in a plane represented by line 3—3 in Fig. 1 of the drawing.

I claim:

The ornamental design for a hat substantially as shown.

In witness whereof, I hereunto subscribe my name to this specification.

EDWARD C. SLOAN.
